UNITED STATES PATENT OFFICE.

CHARLES FRANCIS JENKINS, OF WASHINGTON, DISTRICT OF COLUMBIA.

REVERSING-PROPELLER THROTTLE CONTROL.

Application filed July 23, 1927. Serial No 207,949.

This invention relates to airplanes, and has for its principal object devices for bringing an airplane to a stop promptly after touching the ground and is supplemental to the subject device of Patent No. 1,634,904.

It has been found that reversing the pitch of the propeller blades after the plane has touched the ground, and then opening the throttle of the motor to give reverse power to the propeller, introduces a delay that, if not actually dangerous, certainly is not conducive to the promptest possible stop, often where seconds count because of the high landing speed of some planes.

15 This invention seeks, therefore, to further reduce the hazard of landing by still more promptly stopping the plane after it alights.

With this and other objects in view the invention consists in the novel details of construction and combination of parts more particularly pointed out in the claims.

20 Referring to the accompanying drawings forming a part of this specification, in which like numerals designate like parts in all of the figures:—

Figure 1 is an airplane; Figure 2 the motor-section motor-propeller section of the plane; and Figure 3 the blade-rotating-lever, lock, and throttle-actuating catch.

25 In the several figures, A is a propeller, the blades of which may be rotated about their longitudinal axis; B a collar slidable along the engine shaft, and connected by links C to levers D on the hub-end of each blade; E a

30 loose ring in a groove on collar B, which advances or retracts the collar to partially rotate the blades to give them a different angular attack on the air; F a connecting rod from ring E to the hand lever G, which is in two parts.

35 The two parts of the hand lever are pivoted at H and one of the parts, G', has a notch J in the lower, quadrant-shaped end of it to engage with a latch K. This latch is pivoted at L and has attached thereto rods

40 M and N, one of which, N, is fastened to the tail-skid P, and the other, M, attached to some part of the landing-gear truck, R, which, as usual, supports the plane on springs, i. e., springs between truck and fuselage.

45 S is a safety block on the lower end of lever G, which prevents the latch K from being pulled out by the landing gear until the block is moved from under the latch when lever G is pushed forward. Each of the rods M and N has a spring end Z, so that the shock

of landing does not damage the reversing gear before the lever can be moved. P is a rod attached to the throttle, the opposite end of which has a notch Q therein, to be engaged by the pawl W operable by the latch Y. X is a foot lever to set the whole mechanism back to zero, that is, in locked position for a take-off.

50 The displacement of the safety block S is the first result of the movement of the hand lever G. This forward movement of the lever also brings the pin T on the lever against one of the detents on the upper end of the locked part of the lever, and further movement partially rotates the blades of the propeller. The "further movement" referred to is possible only when the lever is unlocked by the landing gear, either the tail-skid of the truck, or both, coming into contact with the ground.

55 Such setting of the blades "in reverse" renders the propeller effective in stopping the machine when the engine is turned up to such speed as circumstances may require.

60 In order that the power may be turned on in the smallest possible time after the blades are reversed, the same lever which reverses the blades is arranged to open the engine throttle. This saves vital fractions of seconds in the process of a quick stop, where the time the pilot requires to change his hand from reversing lever to throttle might be fatal.

65 After the plane stops, the locking-latch (K) remains out of engagement with the notch J because the weight of the plane on the truck is pushing up on the spring-ended rod M. So to prepare the plane for a take-off and flight the pilot puts his foot on the pedal X and pushes down on the spring, permitting the latch K to enter the notch J and be locked in place by the block S. In such position the regular throttle of the motor is free for service in the usual manner.

70 In these specifications the word ground is used to mean the landing surface upon which the plane comes to rest, and obviously, may be the surface of water, the deck of a ship, an elevated landing platform, or the like.

75 What I claim, is—

1. The combination, in an airplane, of a motor therein, a throttle for controlling said motor, a propeller driven by said motor, reversing gear for said propeller, a lever for controlling the reversing gear, means for connecting said throttle and reversing-gear

lever to insure simultaneous operation of the two, and means for preventing operation of said last mentioned means until the airplane engages the landing surface.

5. 2. The combination, in an airplane, of a motor therein, a throttle for said motor, a propeller driven by said motor, reversing gear for said propeller, means for simultaneously operating the throttle and the reversing gear, and means for locking said means in operative position.

10. 3. The combination, in an airplane, of a motor therein, a throttle for said motor, a propeller driven by said motor, reversing gear for said propeller, means which may be used at will for simultaneously operating the throttle and the reversing gear, means for

locking said operating means, and means operable upon engagement of the airplane with the landing surface for releasing said locking means.

15. 4. The combination, in an airplane, of a motor therefor, a supporting gear therefor, a propeller driven by said motor, reversing gear for said propeller, means for locking said reversing gear, and means for unlocking the same when the plane contacts with the ground, and means for again locking the reversing gear while the weight of the plane is on the ground.

30 In testimony whereof I have affixed my signature,

CHARLES FRANCIS JENKINS
